STOKER

Christ T. Hansen, Chicago, Ill., assignor to The Standard Stoker Company, Incorporated, a corporation of Delaware

Application February 23, 1929, Serial No. 341,867

8 Claims. (Cl. 110—101)

My invention relates to stokers, and has for its general object to provide a new and improved stoker which results in more effective and thorough fuel consumption than prior constructions.

5 In stokers as heretofore made embodying a conduit system for directing and guiding the fuel from the source of supply to the boiler, and further comprising a feeding or conveyor system co-operative with the conduit system for conveying 10 the fuel therethrough; it has been the practice to dispose the discharge mouth or termination of the conduit system at or in the vicinity of the side of the boiler containing the firing door opening. In locomotive boilers the firing door opening is 15 in the rear side or back wall of the boiler and the conduit mouth of the stoker has been either exterior of or interior of the firebox and adjacent the firing door opening, enabling hand firing to be availed of when desired and particularly if 20 there is any failure in operation of the fuel distributing devices that have been associated with the discharge portion of the conduit system for distributing or scattering the fuel over the firebed.

My present invention differs primarily from 25 prior constructions in that the conduit system instead of terminating at the side of the boiler firebox containing the firing door opening is so arranged that its discharge mouth is disposed at the side of the firebox opposite from said open- 30 ing.

The primary advantage of this construction is that the finer and lighter particles of fuel are delivered to the hottest part of the firebed, and the fuel entering the firebox below the roof or 35 arch thereof is forced or directed downward over the firebed, instead of, as heretofore, being carried away unconsumed over the arch through the opening between it and the fire door. The present invention overcomes the prior defect in 40 mechanical stoking boilers of failure to consume the lighter, finer fuel particles, the heating content of which is necessarily lost if they are carried away unconsumed through the boiler flue.

In carrying out the invention practically, it 45 has been found desirable in some constructions where the conduit and feeding systems have extended beneath the boiler grate, to re-design the ash pan so as to conveniently house and protect the systems.

50 In the accompanying drawings various constructions embodying the principles of the invention are disclosed for different styles of stokers and boilers, all of the boilers illustrated being locomotive boilers. It is, however, to be under- 55 stood that the principles of the invention are

readily adaptable to stokers for boilers other than locomotive boilers, the idea being to convey the fuel to a point above the level of the firebed, either inside or outside of the firebox, at or adjacent to the end portion of the grate that is opposite the regular firing door opening, the firing thus being done against the general direction of the draft instead of with it as heretofore and the lighter fuel particles being prevented from escaping and hence of necessity being consumed. 5

To the above and other ends which will hereinafter appear, my invention consists in the features of construction, combinations of devices and arrangements of parts hereinafter described and particularly pointed out in the claims. 10

The invention will be described specifically and in detail in connection with the accompanying drawings, wherein.

Fig. 1 is a fragmentary, vertical sectional view of a stoker applied to a boiler and embodying one 20 form of the invention, only so much of the stoker and the boiler being illustrated as is necessary to a full understanding of the invention;

Fig. 2 is a fragmentary, vertical sectional view taken on a plane indicated by the section line 2, 25 2 in Fig. 1 and looking forward;

Fig. 3 is a view corresponding to Fig. 2 but showing a modification of the ash pan construction;

Fig. 4 is a fragmentary, vertical sectional view 30 generally resembling Fig. 1 but showing a modification of the invention; and

Fig. 5 is a fragmentary, vertical sectional view of another modification.

Referring first to the Figs. 1—2 construction, 35 there is illustrated therein a boiler 10 of the locomotive type embodying a back wall 11 and a throat sheet 12 oppositely disposed from the back wall. The firebox 13 of the boiler has an underlying grate 14 and a roof or arched cover 40 comprising spaced members 15 and bricks or slabs 16 of refractory material.

It will be observed that the cover constituted by the bricks terminates short of the back-wall 45 11, leaving as is usual an opening, designated generally at 17, and that the roof or cover inclines upward from front to rear. The boiler is suitably supported on a locomotive frame indicated at 18, the Fig. 1 construction showing an arrangement whereby the cab is at the rear end 50 portion of the locomotive, the cab deck being designated as 19. It will be understood that the locomotive is coupled or flexibly connected to a tender, not herein disclosed, and that the fuel is supplied from the tender to the boiler by means 55

of a stoker mechanism comprising a conduit system and a feeding or conveyor system only the forward elements of which are shown. The conduit system is disposed on the median plane of the firebox. The conduit system comprises a circular or if desired a U-shaped element section 20 telescoping into a forwardly disposed element 21 connected by a universal joint connection 22 with a horizontally disposed and forwardly extending tubular conduit section or element 23 of circular or U-shaped section. The section 23 extends longitudinally below the boiler and beneath the grate 14 thereof to the forward end portion of the firebox, where the tubular section 23 is telescoped into a curved elbow joint 24, the latter being directed upwardly through an opening 9 in the grates 14 and is connected with a housing or riser 25 disposed within the firebox adjacent the throat sheet 12. The arrangement is such that the discharge mouth 26 of the conduit system is within the firebox 13 and underlying the roof portion 16 thereof.

The mouth 26, it will also be seen, is in effect diametrically opposite from the usual firing door opening designated as 27 in the back-wall 11 and which is ordinarily covered by a closure or door conventionally illustrated at 28. The housing or conduit element 25 is protected by a vertically disposed protecting grating 29 which co-operates with the grate 14 to prevent direct contact between the burning fuel and the conduit system in the boiler area.

The conduit system houses a feeding system comprising flexibly connected conveyor screw sections 30 and 31, the latter terminating at its forward end at the elbow 24. The screw conveyor or feeding means comprising the sections 30 and 31 is mechanically operated, and, it will be understood, will effect a feeding of the fuel from the source of supply on the tender through the conduit system comprising the elements or portions 21, 23, 24 and 25 and upward to the mouth 26 thereof.

Associated, as is usual, with the conduit system is a fuel distributing system or means, which as herein disclosed comprises a distributor head 32 provided with jet forming openings 33 which are connected by pipes 34 with a source of supply of steam or other fluid distributing means, the pressure in the pipes being independently regulated by a valve system, not shown.

In operation, as the fuel passes or is forced upward through the riser 25, its upper portion leaving the discharge mouth 26 of the conduit system will be acted on by the fuel distributing means, in the present instance the steam jets acting to scatter or distribute the fuel rearwardly over the grate 14 or the firebed thereon and in the general direction of the fire door opening 27. It will be seen that the distributor head 32 is disposed between the mouth of the conduit and the top or roof 16 of the firebox and in a comparatively confined space, so that the finer and lighter particles of the fuel, instead of being carried away upward, will be held downward and scattered by the distributor system over the hottest portion of the firebed. This contrasts with prior constructions in which the fuel is distributed from the fire door side, the natural tendency of the draft being to carry the finer and lighter particles upward through the opening 17 before they can be consumed.

In the Figs. 1-2 construction the portion 23 of the conduit system is shown as passing through the ash pan system designated generally as 35.

In order to minimize the chances of the fuel in this portion of the system of coking, by reason of heat transmitted from the ash pan, it may be preferred to modify the ash pan construction to that shown in Fig. 3 wherein an ash pan 36 is shown longitudinally divided to provide a passage-way 37 for the tubular conduit element or section 23.

By the Fig. 3 construction it will be seen that the conduit and its contained screw elements are disposed entirely outside of the ash pan where they are less liable to heating from this source.

In Fig. 4 there is illustrated a modified embodiment of the invention in which the interiorly disposed elbow and riser 24 and 25 of the Figs. 1-2 construction are replaced by an outside arrangement comprising a combined curved elbow and riser element 38 which extends under and outside of the throat sheet 12. The element 38 has a removable cover or top portion 39 which directs the fuel rearward and through an opening indicated at 40 in the throat sheet 12. In this construction the distributing system comprises a distributor table or floor element 41 which projects horizontally rearward through the opening 40 in the throat sheet and terminates just within the firebox.

The fuel distributor system of the Fig. 4 construction comprises a vertical distributor head 42 which is arranged between the conduit element 38 and the distributor table 41 and is located for the most part outside of the opening 40, the jet forming holes 43 in the head acting to scatter and distribute the fuel over the table 41 and thence on to the grate 14 and generally in the direction of the firing door opening which is at the opposite side of the boiler and in the rear wall thereof.

A further modification is illustrated in Fig. 5 adapted for use in a locomotive in which the cab 40 is at the front instead of at the rear, as in the first described construction; and this modification may also be used on locomotives where the engineer's cab is located at the rearward end of the normal boiler location and where the tender 45 and fireman's position are ahead of the boiler. In this Fig. 5 construction, the tender is coupled to the locomotive at the smoke box or stack end thereof, and the stoker extends from the tender beneath the barrel of the locomotive boiler to the hollow wall 12^x adjacent the throat or flue sheet. The locomotive cab is in the usual position with reference to the firebox, but since the tender is at the smoke box end of the locomotive, the cab is thus at the head end of the train whereby greater visibility for the engine crew is afforded. In adapting the invention to this type of construction the conduit system has its forward tubular section 44 connected by a joint 45 with an upwardly and forwardly inclined riser and elbow member 46 having a removable top closure 47 and which is supported on a bracket 46^a. The fuel is thus directed and guided upward and forward to an opening 48 in the throat sheet 12^x. This opening, it will be understood, is at the opposite side of the firebox 13 from the fire door opening as in the prior constructions but with a reversal of position with respect to the locomotive. The distributor table 41 and distributing system involving the distributor head 42 and jets 43 may correspond in the Fig. 5 construction with that disclosed in Fig. 4 and above described.

I claim:

1. The combination, in a locomotive provided with a frame and a firebox above said frame,

5 of a grate in said firebox, and a feed conduit disposed on the median plane of said firebox for delivering fuel thereto, said conduit comprising a riser section rigidly fixed to the front wall of said firebox and having its discharge end positioned above said grate and its receiving end below said grate and a substantially horizontal section disposed below the plane of said grate and at its rearward end being rigidly mounted on said 10 frame and having its forward end loosely fitting the receiving end of said riser section in telescopic relation thereto.

2. The combination, in a locomotive provided with a frame and a firebox above said frame, of a 15 grate in said firebox, a feed conduit section mounted rigidly on said frame at its rear end and extending beneath said grate, the forward end of said section terminating adjacent the front end of the firebox, and a riser conduit member 20 at its lower end portion loosely fitting said conduit section and at its upper end communicating with said firebox at the forward end portion thereof and terminating at a point above said 25 grate, said feed conduit section and said riser member being disposed on the median plane of said firebox, said riser member being rigidly fixed to said firebox, the loose fit between the conduit section and the riser member permitting longitudinal movements between the parts to 30 compensate for expansion and contraction of the firebox on the frame.

3. The combination, in a locomotive provided with a frame and a firebox above said frame, of a 15 grate in said firebox, a feed conduit section having its main portion mounted beneath said grate and terminating adjacent the front end of the firebox, and a riser conduit member at its lower end portion loosely fitting the forward end of said conduit section and at its upper end extending 20 within said firebox adjacent the front wall thereof and terminating at a point above said grate, said feed conduit section and said riser member being disposed on the median plane of said firebox, said riser member being rigidly fixed to the 25 front wall of said firebox and said conduit section being rigidly mounted on said frame at its rear end, the loose fit between the conduit section and the riser member permitting longitudinal movement between the parts to compensate for 30 expansion and contraction of the firebox on the frame.

4. In combination with a locomotive firebox including a front and rear wall and grates, said rear wall having a firing opening therethrough, a fire arch extending rearwardly and upwardly 5 above the level of said grates from said front wall to a point short of said rear wall forming a passage between said rear wall and the rearward end of said fire arch, and a fuel conveyor system disposed on the median plane of the firebox, said conveyor system including a conduit below the level of the grates, an upstanding conduit receiving from said first named conduit and extending upward to a point above the level of said grates adjacent said front wall, means in said first named conduit for urging fuel along said conduit and upwardly through said upstanding conduit to a point below said fire arch, and means at the discharge end of said upstanding conduit for scattering fuel upon the firebed in the general direction of said firing opening.

5. In combination with a locomotive firebox including a front and rear wall and grates, said rear wall having a firing opening therethrough, a fire arch extending rearwardly and upwardly

above the level of said grates from said front wall to a point short of said rear wall forming a passage between said rear wall and the rearward end of said fire arch, and a conduit and conveyor system disposed on the median plane of the firebox beneath the grates for transferring fuel longitudinally of the firebox and under the grates to a point adjacent said front wall and thence upward to a point above the level of said grates and below said fire arch, and means adjacent said front wall at the discharge end of said conduit and conveyor system for scattering the fuel upon the firebed in the general direction of the firing opening.

6. In combination with a locomotive firebox including a front and rear wall and grates, said rear wall having a firing opening therethrough, a conduit system disposed on the median plane of the firebox for directing and guiding fuel from a source of supply to the front end of the firebox, 20 said system comprising a horizontally disposed conduit element extending longitudinally of the firebox and beneath the grates thereof and an upwardly directed conduit element communicating at its lower end with the forward end of said horizontally disposed conduit element and extending upwardly through said firebox grates terminating at its discharge end above said grates and adjacent the front wall of said firebox, and means adjacent said front wall at the discharge end of 30 said conduit system for scattering the fuel upon the firebed in the general direction of the opening in the firebox rear wall.

7. In combination with a locomotive firebox including a front and rear wall and grates, said rear wall and said front wall each having an opening therethrough, a fire arch extending rearwardly and upwardly above the level of said grates from said front wall to a point short of said rear wall forming a passage between said rear wall and the rearward end of said fire arch, a conduit system comprising a portion extending longitudinally of the firebox and under the grates thereof and an upwardly extending portion communicating at its lower end with the forward end 40 of said longitudinally extending portion and at its upper end with the opening in said firebox front wall, and means at the discharge end of said conduit system for scattering the fuel upon the firebed in the general direction of the opening 50 in the firebox rear wall.

8. In combination with a boiler having a substantially rectangular firebox provided with grates, walls bounding said rectangular firebox, one of said walls having a hand firing opening 55 therein, the end portion of said firebox remote from the hand firing opening in the aforesaid wall being provided with a power firing opening, said openings being arranged so that a vertical plane passed along the medial line of the firebox 60 passes approximately centrally of the openings, a fire arch for said firebox extending between the walls thereof and above said openings, said fire arch having an opening therein through which 65 pass the products of combustion in the firebox, the opening in the fire arch being disposed adjacent the firebox wall having the hand firing opening therein, a conduit system for directing and guiding fuel from a source of supply to said power 70 firing opening, said system comprising an approximately horizontal conduit element below the level of the grates, and an upwardly extending conduit element communicating with said horizontal conduit element, said vertical conduit 75

including a discharge mouth disposed above the level of the grates, means in said horizontal conduit for conveying fuel along said horizontal conduit element and upwardly through said upwardly extending conduit element to the discharge mouth thereof, and means for projecting the fuel including a jet member adjacent the discharge

5 mouth of the upwardly extending conduit with its outlets disposed below the fire arch of said firebox, the outlets of said jet member being directed toward the hand firing opening in the aforesaid wall of said firebox and in a plane substantially parallel to the firebox grates.

CHRIST T. HANSEN.
